UNITED STATES PATENT OFFICE.

VICTOR EISELT, OF MUGGIA, NEAR TRIEST, AUSTRIA-HUNGARY.

SCREW-WRENCH.

No. 810,850.

Specification of Letters Patent.

Patented Jan. 23, 1906.

Application filed December 10, 1904. Serial No. 236,370.

To all whom it may concern:

Be it known that I, VICTOR EISELT, a subject of the Emperor of Austria-Hungary, residing at Muggia, near Triest, in the Empire of Austria-Hungary, have invented new and useful Improvements in Screw-Wrenches, of which the following is a specification.

My invention relates to screw-wrenches, and has for its object the construction of a wrench enabling the adjustment of its movable jaw to be effected very quickly and easily.

In the accompanying drawings I have shown by way of example how my said invention may be carried into effect.

Figure 1 is a side view, partially in section, showing the movable jaw locked to the stem. Fig. 2 is a section on the line A B of Fig. 1. Fig. 3 shows the movable jaw disengaged from the stem.

The fixed jaw *a* is carried by the stem or handle *b*, having its front part furnished with teeth *c*. In order to prevent injury to the teeth in the use of the wrench, a rib *d* is provided in the longitudinal direction of the stem or handle *b* in the middle of the teeth *c*, the said rib projecting to the front of these teeth, so that the nut *e* or the head of the screw to be turned may bear against the same, Fig. 1.

The movable jaw *f* has two cheeks *g*, which in the displacement of this jaw slide along the sides of the stem or handle *b*, the said cheeks being connected with each other at the rear by a bridge-piece *h*. The movable jaw *f* of the wrench is locked upon the stem or handle *b* by the following device.

On the outside of the bridge-piece *h* there are two pairs of lugs *i*, these pairs being connected by pins *j*, upon which two armed levers are fitted to turn. The arms *k* of these levers terminate in hooks or noses *l*, having a thickness equal to the depth of the teeth *c*, so that when the said noses are placed between the bridge-piece *h* and the stem or handle *b* the teeth of the movable jaw *f* will be held in engagement with the teeth of the said stem or handle. In this position the lever-arms *k* are kept by the other arms *m* forced outward through the medium of a plate *n*, subjected to the action of a spring *o*. When the movable jaw *f* is to be shifted upon the stem or handle *b*, a button *p*, made in one piece with the plate *n*, is depressed, so as to compress the spring *o*, Fig. 3, the said button by its un-

der surface pressing at the same time upon the arms *m*, thereby removing the noses *l* from the space between the bridge-piece *h* and stem or handle *b*.

In practice the teeth may not with advantage be made less than a certain size, while the clear distance between the fixed and movable jaws should coincide as accurately as possible with the width across the flats of the nut *e* to be turned in order to obviate bruising the edges of the latter. For enabling the width between the jaws to be adjusted to a nicety I provide in the well-known manner in one of the jaws—say in the movable jaw *f*—a thumb-screw *q*, one end of which is connected with a clamping-plate *r* so as to turn therein. It is expedient to make the screw *q* of as large a diameter as possible in order that in the use of the wrench the screw-thread may not be liable to be crushed. The clamping-plate *r* is guided by a rib *s*, furnished on the latter and engaging with a corresponding groove *t* in the movable jaw *f*, the faces of the said rib *s* extending as deeply as possible into the jaw to prevent jamming under strong pressure.

What I claim as my invention, and desire to secure by Letters Patent, is—

1. In a screw-wrench of the character described, a stem carrying the fixed jaw and provided with teeth, a rib formed on the stem in the middle of said teeth, a movable jaw furnished with teeth and a groove which are adapted to engage with the teeth and rib on the stem, levers pivoted to the rear end of said movable jaw, spring-actuated means for forcing these levers into engagement with said stem, a groove formed in the movable jaw, a clamping-plate, and a rib on this plate fitted slidably in said groove.

2. In a screw-wrench of the character described, a stem carrying the fixed jaw and provided with teeth, a rib formed on the stem in the middle of said teeth, a movable jaw furnished with teeth and a groove which are adapted to engage with the teeth and rib on the stem, levers pivoted to the rear end of said movable jaw and having hook-shaped ends, spring-actuated means for forcing said hooked-shaped ends of the levers between said stem and movable jaw, a groove formed in the latter, a clamping-plate, and a rib on this plate fitted slidably in said groove.

3. In a screw-wrench of the character described, a stem carrying the fixed jaw and provided with teeth, a rib formed on the stem

in the middle of said teeth, a movable jaw furnished with teeth and a groove which are adapted to engage with the teeth and rib on the stem, levers pivoted to the rear end of said movable jaw and having hook-shaped ends, a button engaging these levers, a spring acting upon the said button for forcing said hook-shaped ends of the levers between said stem and movable jaw, a groove formed in

the latter, a clamping-plate, and a rib on this 10 plate fitted slidably in said groove.

In testimony whereof I have signed my name to this specification in the presence of two subscribing witnesses.

VICTOR EISELT.
